(57) **CLAIM**

The ornamental design for novelty glasses, as shown and described.

DESCRIPTION

FIG. 1 is a perspective view of novelty glasses showing our new design, where the connectors between the facemask and frame and logo on the temple pieces are shown in dashed lines.

FIG. 2 is a top view of the novelty glasses shown in FIG. 1. FIG. 3 is a front view of the novelty glasses shown in FIG. 1. FIG. 4 is a right side view of the novelty glasses shown in FIG. 1; the left side view of the novelty glasses shown in FIG. 1 is a mirror image of FIG. 4.

FIG. 5 is a back view of the novelty glasses shown in FIG. 1. FIG. 6 is a bottom view of the novelty glasses shown in FIG. 1.

FIG. 7 is a perspective view of novelty glasses according to a modified embodiment, where the connectors between the facemask and frame, logo on the temple pieces, and frame features are shown in dashed lines.

FIG. 8 is a top view of the novelty glasses shown in FIG. 7; and,

FIG. 9 is a front view of the novelty glasses shown in FIG. 7. The right side view of the novelty glasses shown in FIG. 7 is the same as that shown in FIG. 4, but with the frame features shown in dashed lines in FIG. 7 also shown in dashed lines in the right side view; the left side view of the novelty glasses shown in FIG. 7 is a mirror image of FIG. 4, but with the frame features shown in dashed lines in FIG. 7 also shown in dashed lines in the left side view. The back view of the novelty glasses shown in FIG. 7 is the same as that shown in FIG. 5. The bottom view of the novelty glasses shown in FIG. 7 is the same as that shown in FIG. 6, but with the frame features shown in dashed lines in FIG. 7 also shown in dashed lines in the bottom view.

The dashed lines of FIGS. 1–9 are for the purpose of illustrating portions of the novelty glasses and form no part of the claimed design.
